UNITED STATES PATENT OFFICE.

IVERSON D. HUDGINS, OF KIRKWOOD, GEORGIA, ASSIGNOR OF ONE-THIRD TO WILLIAM ISAAC HOBBS, OF GAINESVILLE, GEORGIA.

WATER-MOTOR.

1,329,244.

Specification of Letters Patent. Patented Jan. 27, 1920.

Application filed April 21, 1919. Serial No. 291,549.

To all whom it may concern:

Be it known that I, IVERSON D. HUDGINS, a citizen of the United States, residing at Kirkwood, in the county of Dekalb and 5 State of Georgia, have invented certain new and useful Improvements in Water-Motors, of which the following is a specification.

This invention relates to improvements in hydraulic motors and has for its object to 10 provide a motor in which power is obtained from the vertical oscillation of a pair of arm carried buckets which are alternately filled with and emptied of water deposited therein when the buckets assume an elevated 15 position.

Another object is the provision of a motor of this character in which the pivoted buckets are locked in elevated position until a predetermined quantity of water is deposited 20 therein whereupon the weight of the liquid is utilized to release and permit the bucket to descend under the weight of the liquid contained therein.

Another object is the provision of means 25 facilitating the automatic release of the bucket upon the reception of varying predetermined quantities of liquid so as to vary the power developed by the motor and thereby economize the consumption of water when 30 the motor is carrying a relatively light load.

With these and other objects in view as will appear as the description proceeds the invention comprises the novel features of construction, combination of elements and 35 arrangement of parts which will be more fully described in the following specification and set forth with particularity in the claims appended hereto.

Figure 1 represents a side elevation of the 40 improved motor,

Fig. 2 represents a vertical sectional view on the line 2—2 of Fig. 1, and,

Fig. 3 represents an enlarged detail sectional view through the tank, bucket and 45 valve controlled thereby.

Referring to the drawings in detail, wherein similar reference characters designate corresponding parts throughout the several views the numeral 5 indicates a supporting base carrying an upright frame structure consisting of a series of vertically disposed beams 6 to which the cylinder supporting plates 7 are attached.

A series of horizontally disposed cylinders 55 8 are rigidly supported upon the plates 7

and the cylinders are arranged in pairs, the cylinders of each pair being arranged in superposed relation and provided with reciprocable pistons 9 carrying rods 10. The lower pistons of the opposed pairs are connected by the rods 10 and likewise the upper cylinders of the opposed pairs and the adjacent surfaces of the rods, which latter are preferably offset as illustrated in Fig. 1, are formed with gear teeth which mesh with 60 pinions 11 carried by a power shaft 12 journaled in bearings 13 adequately supported upon the plates 7 and constituting spacing elements. The shaft 12 is rocked back and forth by the mechanism to be hereinafter described and imparts reciprocal movement to the rods 10 through the gears 11.

The frame structure 6 supports an elevated tank 14 preferably of cylindrical form and arranged horizontally. A main supply pipe 75 15 adjacent to which the motor is arranged is connected by a branch pipe 16 with the medial portion of the tank 14 and the end wall 17 of the latter is provided with tubular extensions 18 having flanged inner terminals 19 arranged internally of the tank 14 and constituting seats for valves 20. Each valve is pivotally supported at 21 internally of the tank 14 and is adapted to coöperate with the seat 19 to control the admission of 80 water to the extensions 18. Each valve is connected with a jointed rod 22 which is extended through the end wall 23 of the extension and is connected with the lower terminal of a trip arm 24 pivotally secured to 85 and depending from a supporting rod 25 rigidly supported upon the top of the tank 14.

The rock shaft 12 nonrotatably supports a sleeve 26 confined between the two intermediate brackets 13 and carrying integral radially projecting arms 27 which are preferably arranged at an angle of approximately 90° to each other and are provided terminally with forks 28.

Laterally projecting trunnions 29 carried by each bucket 30 are pivotally mounted adjacent the terminals of the forks 28 and the trunnions are arranged out of line to the diametrical plane of the bucket so that the latter normally tilt inwardly, except that they are counterbalanced by adjustable weights 31 carried on outwardly projecting arms 32 rigidly secured to the outside of the bucket. The top of each bucket is open and, 110

when elevated, is disposed directly under the discharge end of the spout 33 communicating with each extension 18 whereby water is discharged into the bucket when the valve 20 is open. However, the valve is normally retained in closed position by the tension of a spring 34 confined between one of the supporting brackets for each extension 18 and the arm 24, the latter being engageable by a rod 25 carried by the terminals of the forks 28 whereby the valve is automatically opened as the bucket and arm approach the limit of their upward movement.

When the bucket 30 is empty, the force exerted by the weight 31 is sufficient to counterbalance the bucket 30 and retain the latter in outwardly and downwardly inclined position so that the latch 36 carried by the inner portion is engaged behind a keeper 37 carried by the terminal of the tank 14.

In this manner, as the bucket moves upwardly to a position underneath the spout 33, the latch 36 is engaged behind the keeper 37 and the bucket is thus held in elevated position until a sufficient quantity of water has been deposited therein to overcome the weight 31 and tilt the latch 36 out of engagement with the keeper 37 thereby releasing the bucket and permitting the latter to move downwardly under the weight of the water contained therein.

The bottom of each bucket is provided with a discharge opening 38 over which is arranged a pivoted flap valve 39 normally retained in closed position by gravity and adapted to be automatically opened as the bucket approaches the limit of its downward movement by engagement with an upstanding lug 40 carried on a platform 41 upon which the bucket is supported when in its lowermost position.

In operation, the tank 14 is supplied with water by the supply pipe 16 and assuming that the parts are in the position shown in Fig. 1, the rod 25 is engaged with the right hand arm 24, thereby retaining the valve 20 associated therewith in open position and permitting the liquid contents of the tank 14 to discharge into the right hand bucket 30. As the weight of the contents of the bucket 30 reaches a predetermined value the weight 31 is counterbalanced and the latch 36 tilted out of engagement with the keeper 37 thereby releasing the bucket and permitting the latter to move downwardly under the weight of the water contained therein. As the right hand bucket and arm descend the rock shaft 12 is rotated in a clockwise direction moving the pistons 9 in the upper cylinders to the right and producing an opposed movement of the pistons in the lower cylinders and moving the left hand arm 27 and empty bucket carried thereby to an elevated position. As the

right hand bucket approaches the limit of its downward movement, the valve 39 is engaged and opened by the lug 40 thereby permitting the contents of the bucket to discharge. During the discharge of the contents of the right hand bucket, the latch 36 of the left hand bucket locks the arms 27 in the position shown in dotted lines in Fig. 1 and the parts are retained in this position until the left hand bucket is filled and the weight of its contents counterbalances the weight 31 thereby releasing the latch and permitting the bucket to move downwardly, such movement effecting rotary movement of the rock shaft 12 in a counter-clockwise direction and effecting an opposite movement of the pistons 9. If preferred, the cylinders 8 may be provided with air inlet valves (not shown,) through which air is drawn during the suction strokes of the pistons 9 and during the subsequent compression strokes of the pistons the air is discharged through pipes 42.

What I claim is:

1. A motor including a supporting frame, a rock shaft journaled therein, angularly related arms supported upon the rock shaft, pivoted buckets carried by the arms, a tank provided with discharge pipes for conducting water to the buckets when the latter assume an elevated position, means for controlling the discharge water from the tank, counterbalance weights carried by the buckets, a pair of stationary keepers, and latch members carried by the buckets normally retained in engagement with the keepers by the action of the weights and adapted to be disengaged therefrom when the buckets are tilted on their pivotal axes by the counterbalancing effect of the liquid contents thereof.

2. A motor including a frame structure, a rock shaft, angularly related arms connected with the rock shaft, a bucket pivotally mounted in the terminal of each arm, a water supply tank, a discharge pipe communicating therewith, means controlling the discharge of water from the tank, a stationary keeper, a latch carried by the bucket engageable with the keeper to lock the arm in elevated position, an adjustable counterbalance weight acting, when the bucket is empty, to retain the latch in engagement with the keeper and adapted to be counterbalanced by the weight of the liquid contents of the bucket to automatically disengage the latch from the keeper.

3. In a motor, a pivoted arm, a pivoted bucket carried thereby, a rod carried by the arm, a supply tank, a discharge pipe communicating therewith, a pivoted valve controlling the discharge of liquid from the spout, a spring actuated trip arm connected with the valve normally retaining the latter in closed position and disposed in the path

of the rod whereby the valve is automatically opened thereby, and means controlled by the weight of the contents of the bucket to lock the bucket and arm in elevated position.

4. A motor including a frame structure, a rock shaft, an arm carried by the shaft, a bucket pivotally supported in the terminal of the arm, a water supply pipe, a discharge pipe communicating therewith, a relatively stationary keeper arranged adjacent the supply pipe, means carried by the pivoted bucket engageable with the keeper to maintain the bucket in elevated position, and a counterbalance weight carried by the bucket arranged to cause engagement of the retaining member with the keeper when the bucket is empty and adapted, when the bucket is filled, to be counterbalanced by the weight of the contents thereof to cause disengagement of the retaining member from the keeper.

5. A motor including a frame structure, a rock shaft journaled therein, an arm carried by the shaft, a water supply tank provided with a discharge opening, a bucket pivotally mounted upon the arm adapted, when elevated, to receive water from the supply tank, a relatively stationary keeper arranged adjacent the discharge opening, a latch member carried by and movable with the pivoted bucket, an arm carried by the bucket, and a counterbalance weight adjustably mounted upon the arm maintaining the bucket, when empty, in such position as to cause engagement of the latch member with the keeper and adapted, when the bucket is filled, to be counterbalanced by the liquid contents thereof to cause automatic disengagement of the latch member from the keeper. 40

In testimony whereof, I affix my signature hereto.

IVERSON D. HUDGINS.
